Attorney

UNITED STATES PATENT OFFICE

2,034,763

THERMAL TIME SWITCH

Jacob Landau, Jersey City, N. J.

Application September 22, 1936, Serial No. 483,569

1 Claim. (Cl. 200—122)

My invention relates to improvements in time switches, and has among its objects the production of such devices which shall be extremely simple in operation and construction, of comparatively few parts, strong and durable, economical, reliable, and efficient and satisfactory for use wherever found applicable.

It is apparent that there are many instances where it would be highly desirable to have a switch which would turn off the electrical device which it controls, after a substantially predetermined period, this breaking of the electrical circuit to be accomplished automatically. One such place where a switch of this nature would be handy would be the switch that controls the lights in a child's bed room, another place might be the switch that controls closet lights, and there are innumerable other places where lights, motors, or other electrical devices are desired to be shut off automatically after a substantially predetermined time.

It is well-known that thermostatically controlled electrical control devices have been used as "flashers", etc., but in such instances, the current when shut off, will automatically be turned on again after an interval, and the make and break of the circuit will be repeated continuously until the main switch for the circuit is turned off. In the present invention, the current is turned on manually and stays on for a substantially predetermined period of time, preferably from a few minutes upwards, unless turned off manually prior to the automatic shut off, and at the end of the period, will automatically shut off and stay shut off until again turned on manually.

One of the objects of my invention is to provide a thermostatic element that will be thrown into the circuit with the turning on of the switch, and which will become heated up gradually until it will expand sufficiently to actuate the switch release, whereupon the circuit is entirely broken and will remain so until the switch is again manually reset to circuit closing position.

Many other objects and advantages of the construction herein shown and described, will be obvious to those skilled in the art to which this invention appertains, from the disclosures herein given.

To this end, my invention consists in the novel construction, arrangement and combination of parts herein shown and described, and the uses mentioned, and more particularly pointed out in the claim.

In the drawing, wherein I have illustrated preferred embodiments of my invention, and where-

in like reference characters indicate like or corresponding parts throughout the views,

Figure 1 is a plan view of one form of my improved switch;

Figure 2 is a plan view of another form, with certain of the parts in section; and

Figure 3 is a side elevation showing one manner of application of the device.

Referring more particularly to the drawing, the switch shown in Fig. 1 shows the pair of lead contacts 1 and 2, the form shown being a simple single-throw switch, placed in series with any suitable electrical device that is desired to be controlled therefrom, the same not being shown as it forms no part of the invention. The conductors 3 and 4 lead to the contacts 1 and 2, in the well-known manner.

A switch element 5 may be arranged to control the passage of electrical current through the switch, to make or break the circuit, said switch element being movably mounted, as for example by pivotally mounting the same upon the pin 6, although it is to be understood that any desired movable mounting of the switch element may be used.

A heat-expansible element 7, adjacent a heating coil 10, may be interposed in the circuit so that when the switch element is moved to its position to bridge across the contacts or to make the circuit, the coil 10 will receive current from the circuit and will become gradually heated. As the element 10 becomes increasingly heated, the element 7 is correspondingly heated and it expands or elongates, the expansion being dependent upon the characteristics of the particular metal used for the purpose and acting automatically as a heat-actuated thermostat. The element 7 may be operably connected to a latch element 8 which is engageable with the switch element, somewhat in the manner shown, so that when the switch is moved to circuit closing position to turn on the light or other electrical device, the switch element will be held in said position by the engagement with the latch 8.

After the thermostatic element 7 has been heated for a substantially predetermined time, dependent upon the particular material used in its construction, it will have been actuated through a sufficient distance to enable the latch to release itself from the switch element. A spring 9 or other suitable means may be provided to throw the switch element to its normal open circuit position after its release from the latch.

10 indicates the wiring from the contact 1 to the switch element, the same passing about the

thermostatic element 1 to heat the latter, and 11 indicates a switch contact, leading to the other contact 2. From the foregoing description, it will be seen that when the switch element is manually actuated to its circuit closing position, current will energize the thermostatic element and continue to do so until such time as the latter will have been heated sufficiently to elongate the same to release the latch from the switch element, whereupon the switch element will be thrown back to its normal open circuit position.

For various reasons, it may be desirable to provide means for turning off the current sooner than it would be automatically turned off, and for this reason I have provided means operable independently of the thermostatically controlled means, to accomplish this desired end. In the form shown, a lever 12 is positioned to co-operate with the latch 8, said lever being movable to engage with and actuate the latch element to release the switch element. A spring 13 may be arranged to connect with the lever 12 to retract the latter to its normal position after movement thereof.

In the modification shown in Figs. 2 and 3, the device is primarily intended for the control of lights and is therefore more compactly constructed, so that the same may be built as a socket or outlet attachment and into which the electric light may be secured in the usual manner.

One of the contacts leading to the switch is indicated at 14, the same being in series with a coil wound about or otherwise operably connected with a heat expandable or thermostatic element 15 somewhat similar to the element 1 previously described, which in this instance may be more or less arcuate if desired. A hook or latch 16 may be provided at the end of the element 15, or if so desired, this latch may be made separately, and preferably connected to and insulated from the element 15.

A switch element 17 is movably mounted so as to make or break the circuit of electricity through the device, said element being pivoted at 18 in the form shown, and having a spring or other suitable device 19 for retracting said switch element to normal position after release thereof.

The switch contact 20 engages with said switch element in the closed circuit position, and a conductor 21 is shown as leading from said switch element to the electrical device to be controlled through the switch.

When the switch element is moved to the position shown in full lines in the drawing in Fig. 2, as by pulling upon the cord 22 or in any other suitable manner, the switch will be in its circuit closing position and permit current to flow to the electrical device, as for example the lamp shown, the hook of the latch holding the switch in such position until released therefrom.

While in such position, the current will flow through the wire connected to the contact 14 and heat the thermostatic element 15, such heating continuing until such time as the latter has

elongated sufficiently to actuate the latch from engagement with the switch, whereupon the spring 19 will retract the switch and open the circuit, or as shown, will turn off the light.

In order to turn off the light prior to the normal period of time necessary to energize the thermostat sufficiently to automatically accomplish this result, I have provided a cord 23 having one end connected to the thermostat or the hooked end thereof, and the other end adapted to be grasped. When the parts are in the position shown in full lines in Fig. 2, and the cord 23 is pulled, the switch element will be released, and the current will be shut off.

From the foregoing description, it will be seen that I have provided a switch of the kind described, and in which the current may be turned on manually, and will be automatically turned off after a substantially predetermined time, as for example, from between five and ten minutes thereafter, this switch releasing element being operable by the heat from said current. Further, that if it is desired to turn off the current prior to its normal period of operation, the same may be done through the manually operable switch control which will release the latch from engagement with the switch.

Having thus described my invention, it is obvious that various immaterial modifications may be made in the same without departing from the spirit of my invention; hence I do not wish to be understood as limiting myself to the exact form, arrangement, construction, and combination of parts herein shown and described, or uses mentioned, except as limited by the claim.

What I claim as new and desire to secure by Letters Patent is:

In an electrical switch for limiting the period of passing electrical current through a circuit and having a pair of electrical conductors for connection to said source of electrical current; a movably mounted switch member for constantly controlling the passage of said current through said switch; a heating coil in series in said circuit and connected to one of said conductors and operably engageable with said switch member so as to conduct all of the current flowing through said circuit and to become operably heated during the normal flow of said current; a heat-expandable means operably actuated by said coil; a latch controlling said switch member to releasably hold the same in closed-circuit position and constantly actuated by said last-mentioned means during the period that said circuit is closed, to release said switch member after a predetermined amount of movement of said heat-expandable means caused by the full normal flow of current through said switch; and means independent of said heat-expandable means for manually releasing said latch from said switch member at any time prior to its release automatically by said expandable means.

JACOB LANDAU.
